UNITED STATES PATENT OFFICE.

CHARLES S. BURTON, OF OAK PARK, ILLINOIS, ASSIGNOR TO EMIL TYDEN, OF HASTINGS,
MICHIGAN.

PEDESTAL-EXTENSION-TABLE LOCK.

No. 895,071.

Specification of Letters Patent.

Patented Aug. 4, 1908.

Application filed July 1, 1907. Serial No. 381,709.

To all whom it may concern:

Be it known that I, CHARLES S. BURTON,
a citizen of the United States, residing at
Oak Park, in the county of Cook and State
5 of Illinois, have invented new and useful
Improvements in Pedestal-Extension-Table
Locks, of which the following is a specifica-
tion, reference being had to the accompany-
ing drawings, forming a part thereof.

10 The purpose of this invention is to provide an improved device for locking up the members of a pedestal extension table, particularly adapted for use with pedestal extension tables in which the table top members 15 have a limited range of extensibility relatively to their pedestal members; that is, so that the top can be opened to a certain extent without opening the pedestal.

The invention consists of the features of construction shown and described as indicated in the claims.

In the drawings:—Figure 1 is a longitudinal vertical section of a pedestal extension table embodying this invention, the table being shown in closed and locked condition both of pedestal members and top members. Fig. 2 is a similar view showing the middle portion of the table with the top members opened to the extent necessary for admitting one filler and giving access to the pedestal lock, but with the pedestal still locked. Fig. 3 is a detail plan view showing the table-top locking device. Fig. 4 is a detail section at the line 4—4 on Fig. 2.

the line 1-1 on Fig. 2.

35 Without entering into details of the construction for the purpose which is familiar, it may be understood that the table-top members, 1 and 2, are connected with their respective pedestal members, 3 and 4, for extension of the top relatively to the pedestal members; that is, so that the top may be opened or spread apart for receiving fillers to a certain extent without opening the pedestal.

40

45 For locking the two pedestal members together there may be provided any desirable form of locking device adapted to connect said pedestal members when they are near together but before they are completely 50 closed, and to be operated upon when the pedestal members are thus connected for drawing said members tightly together. I have shown for that purpose a latch, 5, pivotally connected to an upstanding lever, 6, 55 which is fulcrumed at its lower end on a ped-

estal member, 3, the latch being located at about the middle of the height of the pedestal and provided with a slope-nosed hook, 5*, at its free end adapting it to ride upon and become engaged with any suitable engaging device, as a staple, 7, on the opposite pedestal member, 4. The latch preferably extends through the center leg, 8, which is apertured at 8^a for the purpose. 69

The lever, 6, has for pivoting at its fulcrum a vertically elongated slot, 6^a, adapting it to be raised and lowered about its pivot in addition to fulcruming thereon in the rocking movement of the lever which is performed when it is at the lower point which it will normally occupy by gravity, except when lifted as hereinafter explained. The latch, 5, is stopped on the lever, 6, so that it will not fall below a proper position extending nearly horizontally for engaging the opposite pedestal member. This is most conveniently effected, in view of the fact that the latch is made of a sheet metal strip folded upon itself, and having two layers riveted together as shown, by making the fold constitute a loop, 5^b, through which the lever, 6, extends for pivotal connection of the latch thereto, the back or cross of the loop, 5^c, being stopped against the back edge of the lever for stopping the latch as described. The lever, 6, extends up to the top of the pedestal and protrudes somewhat there-above in position to be encountered by a finger or thrust rod, 9, which is carried by the opposite table top member and is thrust across the parting plane of the two members above the top of the pedestal and center leg when the two table top members are closed together. It will be seen that with this construction if the latch, 5, is made of such length with respect to the position of the coöperating element on the opposite pedestal member, that the two elements can become engaged while the pedestal members are separated a distance of one inch, the closing up of the table-top members involving the movement of the member, 2, toward the parting plane a distance of over two inches after the finger, 9, encounters the upper end of the lever, 6, or any part thereon provided for such encounter, rocking the lever, 6, over its fulcrum a distance of two inches or more at the upper end, causing it to move one inch or over at the middle point where the latch, 5, is connected to it, will thereby draw the pedestal

members together tightly during such closing movement of the table-top members.

The table-top members may be provided with any means for locking them together, or reliance may be placed entirely upon the frictional hold of the tenons with which they are customarily provided for matching. A catch or positive engaging device is preferable, and I have shown a simple form of spring catch comprising an abutment or hook, 10, on one table-top member and a slope-nosed hook or latch, 11, on the opposite member. Such latch may be located in position for being easily reached by the operator to disengage it when the table is closed, but preferably, the parts, 10 and 11, are mounted near the middle of the width of the table and the latch, 11, is provided with an operating link, 14, extending thence over the top of the 10 slides to the margin of the table where it terminates in a suitable handle, 15, in a position to be easily reached and pulled to disengage the latch.

In the construction as thus far described, it may be understood that the pedestal-locking device is accessible at the top of the pedestal for unlocking the pedestal whenever the table-top members are spread even the distance for admitting one filler. It will also be understood that the pedestal would not be unlocked at all unless it was desired to extend the table so as to admit more fillers than could be admitted by extending the top members relatively to the pedestal. In the structure shown in the drawings it is assumed that the top is to be extended only for admitting one filler while the pedestal remains locked, and there is shown a device by which the pedestal is automatically unlocked when the table-top members are extended farther than this. This device consists of a bell-crank lever, 17-18, fulcrumed on the top of the pedestal member, 3, having a horizontally extending arm, 17, engaging an eye, 6^c, in the upper end of the lever, 6, and an upstanding arm, 18, which is in the path of an abutment 10^b mounted on the under side of the table-top member, 1. As a matter of convenience and because it serves the purpose as well as an additional abutment, I have located the parts so that the plate, 10^a, which carries the catch nose, 10, above mentioned, which forms part of the device for locking the two table-top members together, serves for this encounter having for that purpose the abutment, 10^b, projecting from it, and the position at which the lever, 17-18, is mounted is such as to cause this encounter to occur at some point after the table-top member, 1, has been extended one-half the unit filler width,—that is, its proper amount for admitting one filler. It will be seen that such encounter will rock the lever, 17-18, so as to cause its arm, 17, to pull the lever, 6, upward, as permitted by the slot, 6^a, at its ful-

crum, thus lifting the latch nose, 5^a, clear of the staple, 7, and permitting the pedestal to be opened. If the extension devices are constructed to allow the further extending movement of the table-top member, 1, relative to the pedestal, the plate, 10^a, in such further extending movement will run off the end of the lever arm, 18, and permit the lever to resume its normal position with the latch, 5, dropped to a point at which its nose will encounter the staple, 7, in closing up the pedestal and become automatically engaged therewith. A light spring, 20, is provided operating on the lever, 17-18, to hold it at the position at which the arm, 18, will be encountered, as described, by the abutment, 10, but which will yield to permit the abutment to pass in over the end of the lever arm when the table top is closed up.

I claim:

1. In a pedestal extension table having table top members extensible relatively to their respective pedestal members in combination with such table top and pedestal members, coöperating devices carried by the pedestal members for engaging said members when they are near together and before they are closed, and for drawing the two members together after such engagement; an actuating element by which the drawing movement is communicated extending to the top of the pedestal, and means on one table top member for encountering said actuating element to give said drawing movement at the end of the closing movement of said table top members.

2. In a pedestal extension table having table top members extensible relatively to their respective pedestal members in combination with such table top and pedestal members, a pedestal locking device comprising two elements located at a substantial distance from the top of the pedestal, one on each member of the pedestal, adapted to be engaged with each other, one of said engaging elements being mounted for effecting the engagement and disengagement of said two elements and for drawing the members together after such engagement; an actuating element by which such movement is communicated extending to the top of the pedestal, and means on one table top member for communicating such disengaging movement in the extending movement of said table top member.

3. In a pedestal extension table having table top members extensible relatively to their respective pedestal members, the combination with such table top and pedestal members of coöperating devices carried by the pedestal members adapted for mutual engagement and disengagement, one of said devices being mounted for movement to effect the engagement and disengagement and for relaxing and closing the pedestal

members; an actuating element extending from said movable element to the top of the pedestal member to which said element pertains; operating means mounted on the upper part of said pedestal member for giving said actuating element said engaging and disengaging movement; means mounted on the table top member pertaining to such pedestal member positioned for encountering said operating means to give the disengaging movement in the extending movement of said table top member, and independent means mounted on one of the table top members for giving said actuating element the pedestal-closing movement in the closing movement of said table top member with respect to its pedestal member.

4. In a pedestal extension table having table top members extensible relatively to their respective pedestal members, in combination with such table top and pedestal members, a pedestal locking device comprising two elements located at a substantial distance below the top of the pedestal, one mounted on each member of the pedestal, adapted to be engaged with each other, one of said engaging elements being mounted for two independent movements, one for the engagement and disengagement of said two elements and the other toward and from the opposite pedestal member; an actuating element by which said two movements are communicated extending to the top of the pedestal, and means on one table top member for encountering said actuating element to give the second above-mentioned movement at the end of the closing movement of said table top members.

5. In a pedestal extension table having table top members extensible relatively to their respective pedestal members, in combination with such table top and pedestal members, a pedestal locking device comprising two elements located at a substantial distance below the top of the pedestal, one mounted on each member of the pedestal, adapted to be engaged with each other, one of said engaging elements being mounted for two independent movements, one for the engagement and disengagement of said two elements and the other toward and from the opposite pedestal member; an actuating element by which said two movements are communicated extending to the top of the pedestal, and means on one table-top member for giving said disengaging movement in the extending movement of said table-top member.

6. In a pedestal extension table having table top members extensible relatively to their respective pedestal members, in combination with such table top and pedestal

members; a pedestal locking device comprising two elements located at a substantial distance below the top of the pedestal and adapted for mutual engagement and disengagement, one of said elements being mounted for two independent movements, one to effect the engagement and disengagement and the other toward and from the opposite pedestal member for relaxing and closing the pedestal members; an actuating element extending from said movable engaging element to the top of the pedestal member to which said engaging element pertains; operating means mounted at the upper part of said pedestal member for giving said actuating element said engaging and disengaging movement; means mounted on the table top member pertaining to said pedestal member positioned for encountering said operating means to give the disengaging movement in the extending movement of said table top member, and independent means mounted on one of the table top members for giving said actuating element the pedestal-closing movement in the closing movement of said table top member with respect to its pedestal member.

7. In a pedestal extension table having the table top members extensible relatively to their respective pedestal members, in combination with such table top and pedestal members, a pedestal locking device comprising coöperating elements on the two pedestal members located at a substantial distance below the top of the pedestal and adapted for mutual engagement and disengagement; a vertically positioned lever to which one of said coöperating elements is connected, having a range of vertical movement with respect to its pivot for engaging and disengaging said elements and a range of swinging movement about its pivot toward and from the opposite pedestal member for drawing said members together when the two elements are engaged, said lever being extended to the top of the pedestal member on which it is mounted; means at the upper part of said pedestal member for raising and lowering said lever; means on one table top member for operating said raising-and-lowering means in the movement of said table top member with respect to its pedestal member, and means on the other table-top member for giving the lever the swinging movement in the closing movement of said table top member.

In testimony whereof, I have hereunto set my hand at Chicago, Illinois, this 24th day of June, 1907.
